CLAIM

The ornamental design for an automobile body as shown and described.

DESCRIPTION

FIG. 1 is a front and side perspective view of an automobile body showing our new design;

FIG. 2 is a rear and side perspective view thereof;

FIG. 3 is a front view thereof;

FIG. 4 is a rear view thereof;

FIG. 5 is a side view thereof;

FIG. 6 is an opposite side view thereof; and,

FIG. 7 is a top plan view thereof.

The broken line portions of the automobile body shown throughout the drawing views are for environmental and illustrative purposes that form no part of the claimed design.
